ERASER CLEANER

Frank M. Schaefer, Chicago, Ill., assignor to
 E. W. A. Rowles Company, Arlington Heights,
 Ill., a corporation of Illinois

Application February 11, 1941, Serial No. 378,429

3 Claims. (Cl. 15—6)

This invention relates to machines for cleaning chalk and dust from erasers and confining the same against free escape into the air.

An object of this invention is to provide an improved machine for cleaning erasers.

Another object of this invention is to provide an eraser cleaning machine which is of simple and compact design, efficient in operation and of rugged but light construction so as to be readily carried about for use.

A feature of this invention is found in the provision of a machine for cleaning erasers which is inexpensive in cost and adapted to both clean erasers and to remove chalk dust from the trough or like usually provided about blackboards.

Further objects, features and advantages of this invention will become apparent from the following description when taken in connection with the accompanying drawings in which:

Fig. 1 is a side view of one form of the invention with parts thereof shown in section;

Fig. 2 is a sectional view taken on the line 2—2 of Fig. 1;

Fig. 3 is a fragmentary detailed view showing the assembly of the beaters used in the rotary cleaning device shown in the cleaning machine of Figs. 1 and 2;

Fig. 4 is a view in perspective of another form of the invention;

Fig. 5 is a longitudinal sectional view of the cleaning machine shown in Fig. 4;

Fig. 6 is a sectional view taken along the line 6—6 in Fig. 5;

Fig. 7 is a fragmentary sectional view taken along the line 7—7 in Fig. 6; and

Fig. 8 is a covering means for closing certain of the air inlet passages in the machine shown in Fig. 4, when such machine is being operated to remove chalk and dust from a blackboard trough.

The eraser cleaning machine of this invention includes a rotary cleaning device operatively associated with a suction fan, with the cleaning device and the fan being in operative engagement with a common motor. All three of these elements are enclosed within a housing structure of streamlined contour having an air inlet and an air outlet and means for guiding an eraser to be cleaned across the air inlet. The rotary cleaning device is comprised of both beaters and brushes and is arranged at the air inlet in a manner to operate on the erasers being moved across the air inlet. All of the dust removed from the erasers by the cleaning device

is carried by the suction fan into a dust bag which is connected to the air outlet. The invention contemplates further means for closing the air inlet normally used for the cleaning of erasers and opening a supplementary inlet and attaching to such supplementary inlet a hose or conduit attachment adapted to be moved about to pick up dust or dirt from the usual blackboard trough. The machine is entirely portable and of a construction such that it may be easily carried from room to room of a school building, and when using the blackboard cleaning attachment may be easily carried with one hand while the attachment is manipulated with the other.

Referring to the drawings, there is shown in Fig. 1 an eraser cleaning machine which is comprised of a standard or frame member 10 having a base portion 11 at its lower end provided with legs 12 for standing the machine in an upright operating position and a handle portion 13 at its upper end for carrying the machine around. Intermediate the base portion 11 and handle portion 13 is a cavity or chamber 14 open at both ends, a housing member 16 for a rotary cleaning device 17 being connected to the member 10 at one end of the cavity 14 and a housing member 18 for an operating motor (not shown) being connected to the member 10 at the other end of the cavity 14. The motor is separated from the chamber 14 by a partition or separating plate 19 which extends transversely across the inner end of the housing member 18, the outer end of the housing 18 being closed. A projecting end portion 21 of the motor shaft is rotatable in the partition plate 19 and extends therethrough completely across the chamber 14 and the cleaning chamber 22 within the housing element 16, the chambers 14 and 22 being open to each other. The free end 23 of the shaft portion 21 is rotatably supported in a bearing member 24 mounted in a boss portion 26 formed at the closed end 27 of the housing member 16. An air fan 28 is suitably mounted about the shaft portion 21 and within the cavity 14, the cleaning device 17 being also mounted on the shaft portion 21 but axially displaced from the fan 28 for location in the chamber 22. From the above description and consideration of Fig. 1, it is seen that the chambers 22, 14, and the chamber for the motor are arranged longitudinally of the machine housing structure designated generally as 29, with the fan 28, and cleaning device 17 being mounted on the motor shaft in direct driven engagement with the motor. Although

the housing structure 29 is illustrated as being formed of three component parts it is to be understood that it may be modified to include a lesser number of parts without in any manner affecting the improved arrangement and assembly of the machine operating elements.

The housing member 16 is integrally formed at the top thereof with a track portion 31 which extends transversely of the cleaning machine and parallel to the handle portion 13 (Fig. 2). The track portion 31 is of substantially trough shape section and is extended equally on opposite sides of the housing member 16 with each extension being of a length to conveniently support an eraser 32 thereon. An air inlet 33 which opens into the cleaning chamber 22 is formed in the bottom 42 of the track portion 31 about centrally of the track ends. As an eraser 32, therefore, is moved along the track portion 31, it is guided by such portion for passage across the opening 33. The cleaning device 17 within the cleaning chamber 22 is arranged transversely of the track means 31 and across the opening 33 in a manner such that the device rotates in a direction longitudinally of the eraser 32 which is to be cleaned, as will be explained.

The cleaning device 17 is comprised of a hub member 34 having integrally formed annularly extending flange portions 36 at its opposite ends. A plurality of brushes 37 are angularly spaced in axial alignment about the hub, the brushes extending radially from the hub to provide a brush assembly of cylindrical form. Also angularly spaced about the hub 34 and positioned between certain of the brushes 37 are centrifugally actuated wire beaters 38. The outer ends of the beaters 38 are of hooked shape and are positioned in the circumference of the brushes 37. The inner ends of the beaters 38 are of substantially eyelet shape for pivotal connection to a rod 39 which is positioned axially of the hub portion 34 and mounted in the annular flange portions 36. As is shown in Fig. 3 each rod 39 is formed with axially spaced annular grooves 41 which are adapted to receive therein the eyelet portions of the beaters 38. In the arrangement of the cleaning device 17 relative to the opening 33 it is contemplated that the bottom 42 of the track portion 31 be substantially tangent to the circumference of the cleaner 17 so that the eraser 32 in passing over the cleaning device is operated on by a brushing or sweeping action. Where the cleaning device projects an appreciable amount through the opening 33 and above the bottom 42 of the track portion, it tends to scrape and pull the bottom of the eraser 32, so as to appreciably shorten the service life thereof.

In the operation of the machine shown in Figs. 1 and 2 the extension cord 43 is plugged into a convenient electrical outlet and the motor for operating the fan 28 and the cleaner 17 is turned on by the switch 44, which is mounted in the motor housing 18. It is contemplated that the cleaner 17 be rotated in a clockwise direction, as viewed in Fig. 8, and that the eraser 32 be slid along the track portion 31 in a direction from right to left, as also viewed in Fig. 2, so as to be moved into the direction of rotation of the cleaner 17. As the eraser moves across the rotary cleaner it is alternately engaged by the beaters 38 and a series of brushes 37, the beaters providing a rubbing or sliding impact on the eraser to loosen the dust therefrom and the

brushes 37 functioning to sweep this loosened dust away from the eraser. The dust which is thus removed is carried through the chambers 22 and 14 by the action of the fan 28 and is discharged from the chamber 14 through an opening or outlet 46 formed therein. A dust bag 47 of a type usual in vacuum cleaners is suitably connected to the outlet 46 for catching and collecting the dust.

As the eraser 32 is moved along the track portion 31 a position is reached such that the inlet 33 is completely covered and closed by the eraser. This closing of the inlet 33 not only reduces the efficiency of the fan 28 in removing the chalk dust from the chambers 22 and 14, but also increases the load on the operating motor by virtue of the fan 28 operating against the closed chamber 22. In order to continuously discharge from the machine the chalk dust which is being removed from the erasers and to eliminate any overloading of the operating motor, air passages 48 and 48A opening into the chamber 22 are formed in the track portion 31 at a point below the inlet 33. When the inlet 33, therefore, is closed by the positioning of an eraser thereover, air is by-passed about the opening 33 and into the chamber 22 through the passages 48 and 48A. A continuous flow of air is thus maintained through the chambers 14 and 22 at all times during the cleaning operation so that the motor always operates with a substantially constant load. It is apparent, of course, that prior to the closing of the inlet 33 some air will pass through the passages 48 and 48A as well as through the inlet 33. However, the air passing through these passages at such times does not interfere in any way with the efficient operation of the rotary cleaner 17 and the suction fan 28.

In the machine illustrated in Figs. 4 to 8, the housing means or structure 29' is similar in all respects to the housing structure 29 previously described in connection with the machine in Figs. 1 and 2, except for the telescopic engagement of the cleaner housing 16' with the frame member 10'. The telescopic engagement of both the cleaner housing 16' and the motor housing 18 with the frame member 10' provides for an improved alignment of these housing members and for a more rigid construction of the housing structure. The track portion 31 and air inlet or cleaning opening 33 of the housing member 16', however, are similar in all respects to the same parts in Figs. 1 and 2, also for the purpose of reducing the overall weight of the machine the base portion 11' of frame member 10' is cut away between the legs 12, as is clearly shown in Fig. 4.

The motor (not shown) for operating the air fan 49 and rotary cleaner 51 (Fig. 5) includes a motor shaft having an end portion 52 which extends through the partition plate 19 into the fan chamber 14'. The shaft portion 52 is threaded over a portion of its length for threaded engagement with an inner fan hub 53 which has a correspondingly threaded inner bore. It is contemplated that the outer fan hub 55, fan blades 85, and fan back plate 61 be integrally formed by die-casting. The hub 53 may be provided in steel or like metal and is formed with annularly extending portions 86 and 87 near one end thereof. The portion 87 is positioned between the back plate 61 and a circular disc or plate 88 formed of sheet metal and spot-welded or otherwise secured to a bracing plate 89 mounted on the back plate

61 by rivets 90. The discs 88 and 89 and the hub 53 may be preassembled prior to their assembly to the remaining die cast fan portion. On riveting of the disc member 89 to the back plate 61, therefore, there is provided a fan assembly of rugged and integral construction. By virtue of the steel hub portion 53 there is assured a positive threading with the shaft portion 52 to mount the fan 49.

The partition member 19 near its center part is formed on one side with a pressed out portion 10 91 corresponding in shape to a cup member 92 secured by screws 93 to the opposite side of the partition member 19. The portions 91 and 92 provide a housing for a bearing unit having a bearing portion 94 and spacer means including a felt washer 96, a steel washer 97 and a retaining ring 98. The shaft portion 52 is journaled directly in the bearing portion 94 while the steel washer and plate portion 91 are engageable with the hub portion 53 of the fan 54, the annular shoulder 86 defining the position of the hub portion 53 within the bearing unit. Since the opposite end of the motor shaft (not shown) is rotatably supported in the housing portion 18, the bearing unit eliminates any necessity for an accurate aligning of the shaft bearings thus eliminating assembly difficulties and correspondingly reducing manufacturing costs. Any misalignment in the shaft bearings, therefore, is compensated for by the bearing unit without impairing the service life or operating efficiency of the machine. It is contemplated further that the fan assembly 49 be threadable on the motor shaft 52 in the direction of rotation of the motor to assure its being tightly held on the shaft at all times.

A fan 99 for cooling the motor is formed with a cup-shaped hub portion 100 corresponding in form to the cup-shaped member 92 and fitting in part over such latter member, the fan 99 being suitably mounted on the shaft end 52 for concurrent rotation therewith. It is thus seen that the assembly of the fan 49, the motor fan 99 and the bearing for the motor shaft is simply and compactly arranged in a minimum of space. This assembly includes further the rotary cleaner 51 which is mounted on and threadably engaged with the outer hub portion 55 of the fan 49.

The rotary cleaning device 51 (Figs. 5 and 6) is comprised of a tubular hub or body portion 56 having angularly arranged radially extending flange portions 57 thereon axially spaced apart a distance substantially equal to the width of the cleaning opening 33. The hub portion 56 is formed with an extension 58 which projects into the impeller chamber 14', such extension being internally threaded for threaded engagement with the outer fan hub 55. By virtue of this construction and assembly of the motor, fan 49, and rotary cleaning device 51, the fan and cleaning device are in direct driven engagement with the motor while being positioned in their respective chambers. In the practice of this invention it is contemplated that the hub extension 58 of the rotary cleaner 51 be of a length such that on engagement of the extension end 59 with the fan back plate 61 the flange portions 57 will be disposed on opposite sides of the opening 33, thus positioning the cleaner in an operating position relative to the opening. The hub portion 56 between the flange portions 57 is formed with a series of longitudinally aligned apertures 62, each of which is adapted to receive therein a brush 63. The brushes 63 for each axial row are retained in their corresponding apertures 62 by a

wire 64 which is weaved about the brushes and through the apertures in a manner clearly illustrated in Fig. 5. Each pin or rod 39 for supporting the beaters 38 is mounted in a pair of corresponding flange portions 57 for arrangement between certain of the brushes 63, the relation of the beaters 38 and brushes 63 in the device 51 being similar to the brush and beater arrangement of the cleaner 17 in the machine of Figs. 1 and 2.

As shown in Figs. 6 and 7 the bottom 42 of the track portion 31 is built up with shims or plate members 66, the number and thickness of the plates depending upon the particular operating conditions for the machine. The plates 66 are secured to the track 31 by screws 67 which are seated beneath the surface of the uppermost plate 66 so as not to interfere with the passage of an eraser 32 thereon. In the initial assembly 15 of the machine, therefore, the cleaning device 51 is arranged so that the uppermost plate 66 is tangent to the brush circumference. During the 20 use of the machine the brushes 63 become worn so that in time the efficiency of their cleaning action on the eraser is appreciably reduced. It is contemplated, therefore, that the plates 66 be 25 separately removable from the track bottom 42 in accordance with the wear of the brushes 63 so that a substantially tangential relation of the 30 bottom of the track with the circumference of the brush is maintained at all times. In this manner an efficient and positive operation of the brushes 63 is assured over the entire service life of the machine. Since the plates 66 may be provided in 35 a relatively cheap material, it is apparent that this construction appreciably reduces the servicing costs of the machine by prolonging the active life of the rotary cleaner 51 and hence eliminating frequent replacements thereof.

With the rotary cleaner 51 and the upper one 40 of the plates 66 in their relative tangential arrangement, the operation of the machine of Fig. 4 is similar in all respects to the operation of the machine in Fig. 1, so that a description of 45 such operation is believed to be unnecessary. During this operation, however, it sometimes occurs that chalk dust is discharged through the supplementary air passage 48A which is positioned in the track portion 31 in the direction of 50 rotation of the cleaner 51. With the cleaner rotating in a clockwise direction, as viewed in Fig. 6, this passage is seen to be the one located at the right end of the track portion 31, as also viewed in Fig. 6. To eliminate this undesirable 55 discharge of dust a flap valve 68 is positioned over the inner end of the passage 48A but clear of the travel of the cleaner 51. The valve 68 includes a supporting pin 69 which is suitably mounted in the rib or brace portions 71 of the housing member 16'. Assemble of the pin 69 in the portions 60 71 is facilitated by its insertion into an assembled position through the aperture provided in the housing member 16' for the connecting screw 72. Positioning of the valve 68 transversely of 65 the passage 48A is accomplished by supporting the flap or ear portions 73 about the reduced pin sections 74. Since the valve 68 is freely rotatable on the pin 69 it is entirely responsive to the difference in the velocity pressures in the passage 70 48A and chamber 22' to open and close the passage 48A. The closed position of the valve 68 is determined by a shoulder 76 formed at the bottom of the passage and in the rib portions 71.

When the machine of Fig. 4 is operated for 75 cleaning erasers, the flow of air in the chambers

22' and 14' is through the air inlet 33 and passages 48 and 48A and air outlet 46. During this operation a supplementary or second air inlet 77 formed in the closed end 78 of the housing member 16' is closed by a cover plate or cap 79. Positioning of the inlet 77 in the housing end 78 is provided by virtue of the bearing support of the motor shaft in the plate 19, thus leaving the housing end 78 entirely free of any bearing means for the shaft. The inlet 77 is adapted for connection with a suitable hose attachment (not shown) which may be manually manipulated to lift or remove chalk dust from around a blackboard and particularly from the blackboard trough. In the operation of the machine in this manner it is desirable, of course, that the greatest suction effect of the fan 49 be at the inlet 77. It is necessary, therefore, that at such times the inlet 33 and passages 48 and 48A be closed, so that the flow of air in the chambers 22' and 14' is entirely through the secondary air inlet 77. This is accomplished by covering means 81 (Fig. 8) which includes a pair of U-shaped clamps or clips 82 connected together by an elastic band 83. The band 83 is of a width to fit transversely across the bottom 42 of the track portion 31, while a clamp 82 is adapted to fit about each end of the track portion to cover a corresponding passage 48 and 48A. The covering means 81 is retained in position over the inlet 33 and passages 48 and 48A by virtue of the tension in the elastic band 83. With the passages 48 and 48A and opening 33 thus closed it is clear that the fan 49 can draw air into the chamber 22' only through the air inlet 77 and its associated hose attachment. In the cleaning of a blackboard trough, therefore, the machine is carried in one hand by the handle portion 13 while the hose attachment is manipulated with the other. Because of the tangential relation between the rotary cleaning device and the bottom 42 of the track portion 31, the brushes 63 and beaters 38 do not in any way interfere with the closing of the air inlet 33 by the band member 83. When the machine is to be operated for cleaning erasers, it is only necessary to remove the covering means 81 and to replace the cap member 79 over the air inlet 77.

The invention thus provides a machine for cleaning erasers which is simple and compact in construction, efficient in operation, and assembled in a manner to provide a streamlined contour of pleasing appearance. The machine is very inexpensive in cost and is thus commercially available to any school having a source of electricity. Although the cleaning machine is adapted to both clean erasers and chalk dust from around the blackboard, it is nevertheless very light in weight and may be easily carried about in one hand.

The present invention has been described and illustrated with reference to several preferred forms thereof, but it is to be understood that changes therein can be made which are within the full intended scope of this invention as defined by the appended claims.

I claim:

1. In a machine for cleaning erasers including rotary cleaning means and fan means operatively associated with said rotary cleaning means, the combination of means for housing said two means, said housing means having an air chamber therein with an inlet and an integrally formed track portion for guiding erasers across said in-

let, said rotary cleaning means being positioned at said inlet to remove the dust from the erasers moved across said inlet, with said erasers being of a length to extend entirely across the inlet to close the same, said chamber having an air outlet positioned relative to said fan means so that the dust removed from said erasers by said rotary cleaning means is discharged therethrough from said housing means, and means for bypassing the air about said air inlet when said inlet is closed by an eraser so that the dust is continuously discharged from said machine regardless of the position of an eraser relative to said inlet, said latter means including an air passage in said housing means connecting said air chamber with the atmosphere.

2. In a machine for cleaning an eraser having rotary cleaning means, suction means operatively associated with said cleaning means, and a driving motor common to said two means, the combination of housing means for said three defined elements having a cleaning chamber and a suction chamber, said cleaning means being located in said cleaning chamber and said suction means being located in said suction chamber, with said two chambers being open to each other, said housing means having an inlet opening therein at said cleaning chamber and an outlet opening therein at said suction chamber, with said suction means operating to provide a flow of air in said two chambers through said two openings, and track means at said inlet opening for guiding an eraser to be cleaned across the same, said cleaning means being positioned at said inlet opening to operate on said eraser to remove the dust therefrom, with the dust from said eraser being carried by said air flow and discharged from said machine through said outlet opening, said eraser during its movement along said track means extending across said inlet opening to stop the flow of air into said cleaning chamber, so that the load on said motor produced by said suction means is greatly increased, and by-pass means including an air passage in said track portion connecting said cleaning chamber with the atmosphere for admitting air into said cleaning chamber when said inlet opening is closed to prevent said motor from becoming overloaded.

3. In a machine for cleaning erasers having rotary cleaning means and suction means arranged in a cooperating relation with said cleaning means, the combination of means for housing said two means including a chamber for said rotary cleaning means, said housing means having an air inlet and an air outlet in operative association with said suction means and a passage adapted to by-pass air about said inlet, means for guiding an eraser to be cleaned across said air inlet, means rotatably supporting said cleaning means at said inlet for operation on said eraser, with the dust removed from said eraser by said cleaning means being discharged through said outlet, said eraser during its movement across said inlet closing the same and effecting a change of air pressure in said chamber, and valve means in said air passage operable in response to the air pressure in said chamber and arranged to close said passage when said inlet is open, and to open said passage when said inlet is closed by an eraser to provide for a substantially continuous discharge of dust from said outlet.
